UNITED STATES PATENT OFFICE.

NILS J. A. WAHLBERG, OF PITTSBURGH, PENNSYLVANIA, ASSIGNOR TO WESTINGHOUSE ELECTRIC & MANUFACTURING COMPANY, A CORPORATION OF PENNSYLVANIA.

FEED-WIRE CONNECTER.

Application filed May 2, 1919. Serial No. 294,306.

To all whom it may concern:

Be it known that I, NILS J. A. WAHLBERG, a citizen of the United States, and a resident of Pittsburgh, in the county of Allegheny and State of Pennsylvania, have invented a new and useful Improvement in Feed-Wire Connecters, of which the following is a specification.

My invention relates to electrical connectors and particularly to connectors for tapping main-line or trolley conductors.

One object of my invention is to provide a device of the above indicated character that shall be simple and durable in construction and effective in operation.

Another object of my invention is to provide a portable connector, for temporary or permanent connection to a conductor, that shall be readily operable by hand, without the aid of instruments or tools.

Heretofore, to the best of my knowledge, it has been usual, in tapping conductors adapted for relatively-high-voltage or heavy-current service, to employ connectors requiring the use of instruments or tools for mounting them.

One adaptation of such connectors has been in coal mines, for use in connection with coal-working machines, where facility of operations is desirable.

Screw-threaded, and otherwise-complicated, connectors, requiring the use of tools, are subject to deterioration by moisture and other causes and may cause inconvenience and loss of time when the tools therefor are lost or misplaced.

In practicing my invention, I provide a portable connector, comprising simple and durable members that are not likely to quickly become affected by wear, moisture or rough usage, and that may be easily operated by hand without the aid of separate instruments or tools of any kind.

Figure 1 of the accompanying drawings is a plan view of a connector embodying my invention; Fig. 2 is a side elevational view of the same; Fig. 3 is a view taken along the line III—III of Fig. 2, and Fig. 4 is a view taken along the line IV—IV of Fig. 2.

In general, my device comprises a pair of clamping jaws or ears 1 for engagement with, and that conform to, a usual figure 8 trolley conductor 2 but that may be adapted to conductors of other forms, an intermediate clamping or wedging member

3, an operating handle 4 and, an auxiliary conductor 5.

The members 1 and 3 co-operate similarly to members shown in Patent No. 931,390 for a trolley clamp granted to the Westinghouse Elec. & Mfg. Co., Aug. 17, 1909, upon an application filed by Harry P. Davis, and are provided with sloping portions or lugs 6 that are embraced by co-operating lugs 7 on the member 3. A projection 8 of the member 3 extends between the upper portions of the ears 1 to a position between a pair of side cam portions 9 of a member 10. A cotter pin 11 extends transversely through the portions 9 and the projection 8 and serves as a pivot about which the member 10 is adapted to turn. As best shown in Fig. 2, the portions 9 are eccentrically related to the pin 11 and bear against the outer edges 12 of the ears 1. A terminal member 13, for the reception of the auxiliary conductor 5, is secured between the member 10 and the operating handle 4 by a screw bolt 14 that extends through the members 10 and 13 longitudinally into the handle member 4.

In the position shown in the drawings, the ears 1 tightly grip the conductor 2 by reason of the fact that the greatest radii of the portions 9 extend from the pin 11 to the nearest points on the edges 12, thereby compelling the lugs 7 to grip the lugs 6 to hold the ears 1 together.

When the handle member 4 is moved away from the conductor 2, about its pivot, the decreasing radii of the portions 9 between the pin 11 and the edges 12 permits the member 3 to move toward the conductor 2 to release the lugs 7 from the lugs 6. This permits the ears 1 to be detached from the conductor 2.

The arrangement provides a simple and effective means for tapping a conductor at any point, is portable and, being operable by hand without the aid of instruments or tools of any kind, prevents the inconvenience and loss of time sometimes occasioned by the loss of these implements.

While I have shown and described a particular form of my invention, changes may be effected therein, without departing from the spirit and scope thereof, as set forth in the appended claims.

I claim as my invention:

1. In a clamp, the combination with a pair of complementary jaw members having

substantially flat inclined surfaces and a clamping block having similarly inclined surfaces which engage said jaw members, of means comprising a pivoted handle member 5 for adjusting the inclined surfaces of said block against the corresponding inclined surfaces of said jaw members.

2. In a clamp, the combination with a pair of complementary jaw members having substantially flat inclined surfaces and a clamping block having similarly inclined surfaces which engage the corresponding inclined surfaces of said jaw members, of a handle member pivoted to said block and 15 having a cam portion for engagement with said jaw members.

3. In a clamp, the combination with a pair of complementary jaw members having substantially flat inclined surfaces and a clamping block having similarly inclined surfaces which engage the corresponding inclined surfaces of said jaw members, of a handle member eccentrically pivoted to said block and having a portion for engagement 25 with said jaw members.

4. In a clamp, the combination with a pair of complementary jaw members having inclined outer surfaces, and a clamping member having portions embracing said jaw 30 members and engaging said inclined surfaces, of means comprising a handle member pivotally associated with the clamping member for wedging said clamping member against the inclined surfaces of said jaw 35 members.

5. In a clamp, the combination with a pair of complementary jaw members having inclined outer surfaces, and a clamping mem-

ber having portions embracing said jaw members and engaging said inclined surfaces, of means comprising a cam member for adjusting said block against said inclined surfaces. 40

6. In a clamp, the combination with a pair of complementary jaw members having inclined outer surfaces, and a clamping member having portions embracing said jaw members and engaging said inclined surfaces, of means comprising a pivoted eccentric cam member for adjusting said block 45 against said inclined surfaces. 50

7. In a clamp, the combination with a pair of co-operating jaw members one of which has a substantially flat inclined outer surface, and a clamping member having portions embracing said jaw members, one portion of said clamping member engaging said inclined surface, of means comprising a handle member pivotally associated with the clamping member for wedging said 55 clamp member. 60

8. In a trolley clamp, the combination with a plurality of jaw members, of means for wedging one member toward another and means for camming said first means 65 into an operative position.

9. In a trolley clamp, the combination with a plurality of jaw members, of a block for wedging said members one toward another, and means for camming said block 70 into its operative position.

In testimony whereof, I have hereunto subscribed my name this 25th day of March, 1919.

NILS J. A. WAHLBERG.
